UNITED STATES PATENT OFFICE

ANDREW REED ROWE, OF MIDLAND, PENNSYLVANIA

FEEDER FOR INGOT MOLDS

Application filed January 15, 1927. Serial No. 161,353.

This invention relates to an apparatus for and method of casting metal products and is an improvement on my apparatus and method as described in my Patent 1,399,798, patented December 13, 1921.

An object of the present invention is to improve the reservoir used in the top of the mold and its method of manipulation.

Another object of the invention is to construct the reservoir mainly of wood, preferably lined with metal and so shaped as to rest in the top of the mold and support a bottom of refractory material with holes therein, gas vents between the floating reservoir and the top of the mold being provided for the escape of gas as the metal is poured into the mold.

Another object of the invention is that the refractory bottom of the reservoir will be floated on the top of the metal as it is poured into the mold and will retain the heat in the metal at the top of the ingot as is desired.

With these and other objects in view, which will be apparent as the description proceeds, I will now describe my invention in connection with the accompanying drawings in which:

Figure 1 is a plan view; and,

Figure 2 a sectional view of a mold with the reservoir therein. Figure 3 is a modified form showing the reservoir on top of the mold.

1 is the mold which may be of the usual rectangular construction and 2 is the reservoir. I prefer to construct this reservoir with wooden sides 3 and line the same on the interior with metal sheets 4. The lining may extend from the top of the reservoir to near the bottom and is there provided with lugs 5 by suitably bending the sheets inwardly, then downwardly and then outwardly at 6 so as to cover the sides and bottom of the wooden portions 3.

Preferably I provide lugs 7 at the top of the reservoir so as to support the reservoir 2 in the mold by the lugs 7 and leave vent spaces between the interior of the wooden reservoir and the interior of the mold.

I also provide a bottom 9 for the reservoir 50 of refractory material having vents 10 there-

in, the bottom 9 resting on the inwardly projecting lugs 5 of the reservoir.

With this apparatus, when pouring the metal into the mold through the reservoir and the holes in the bottom of the same, as the metal rises in the molds and reaches the bottom of the reservoir, the reservoir will be floated by the metal as the mold continues to be filled, and the refractory bottom of the reservoir will retain the heat in the metal at the top of the ingot as is desired.

The wood of the reservoir may be burned by the hot metal, but it will leave no débris that will be difficult to remove after the pouring operation is completed. The metal lining of the reservoir will of course be almost instantaneously heated to the temperature of the molten metal. Since the lining is very thin, it will have little effect in chilling the molten metal.

As the main stream of metal will soon cover the bottom 9 of the reservoir and as it continues to flow through the holes 10 into the mold 1, gas vents must be left between the reservoir and the interior of the mold. This is most conveniently effected by leaving a space between the reservoir and the interior of the mold top and providing vents 12 in the lugs 7.

The operation of my molds is apparent from the foregoing, but to summarize, the metal is poured into the reservoir, in a comparatively large stream which is broken up, when it strikes the bottom of the reservoir, into smaller streams through the openings 10 as more fully set forth in my patent before mentioned. The metal will continue to run into the mold and as it rises, the gases will escape around the reservoir and out through the vents. When the molten metal reaches the bottom of the reservoir it will almost instantly heat the metal lining of the reservoir to practically the temperature of the molten metal. The wood portion of the reservoir being a nonconductor of heat, will prevent excessive chilling of the metal at the top of the mold which is always desirable. The reservoir will be floated to the top of the mold and may be removed with a minimum of trouble and the material of the reservoir

being of non-heat conducting properties, will diminish to a minimum the chilling of the metal at the top of the mold.

What I claim is:

- 5 1. An apparatus for molding metal comprising a reservoir member adapted to be seated in the upper end of a mold, the sides of said member being constructed of wood, and lined on its interior with thin metal, a bottom supported on the interior of the reservoir with holes therein, the reservoir being sufficiently small to leave vents between the exterior of the reservoir and the interior of the top of the mold for the escape of gases.
- 10 2. An apparatus for molding metal comprising a reservoir member adapted to be seated in the upper end of a mold, said reservoir member comprising a wooden casing with lugs on its exterior on which the reservoir rests, and an interior lining of thin metal extending under the wooden casing the reservoir being sufficiently small to leave vents between the interior of the top of the mold and the exterior of the sides of the reservoir, said reservoir having a bottom of refractory material with holes therein, said bottom being supported near the bottom of the reservoir.
- 15 3. An apparatus for molding metal, including a reservoir member adapted to be seated on the upper end of a mold, said member being constructed of inflammable material interiorly lined with thin metal said lining projecting inwardly to form a ledge, and a bottom for the reservoir having holes therein, said bottom being supported by said ledge in the reservoir.

In testimony whereof I affix my signature.
ANDREW REED ROWE.
